UNITED STATES PATENT OFFICE.

JAMES C. DALEY, OF CHICAGO, ILLINOIS, ASSIGNOR TO JEFFERSON ELECTRIC MFG. CO., OF CHICAGO, ILLINOIS, A CORPORATION OF ILLINOIS.

MOUNTING FOR FRANGIBLE CONTAINERS AND THE LIKE.

Application filed November 20, 1924. Serial No. 751,036.

To all whom it may concern:

Be it known that I, JAMES C. DALEY, a citizen of the United States, residing at Chicago, in the county of Cook and State of Illinois, have invented a certain new and useful Improvement in Mountings for Frangible Containers and the like, of which the following is a full, clear, concise, and exact description, reference being had to the accompanying drawings, forming a part of this specification.

My invention relates to mountings for frangible containers and the like, and more particularly for open transformer containers of porcelain or other insulating material, although the invention is not limited to a particular use or purpose.

In transformers, especially those of the relatively small, bell ringing type, it is desirable to use a container of porcelain or other suitable insulating material. To permit mounting the device as desired, these containers have usually been provided with integral mounting lugs. These are, however, quickly fractured or broken off in drawing up the screws or other fastening means. Where lugs of this sort are broken off, proper mounting of the device has been impossible and it has been necessary to discard or scrap the entire container. These mounting lugs have also been susceptible to breaking or fracture in shipping, transporting and handling the containers because of their frangible character and their projection from the container.

The object of my invention is the provision of a generally improved, simple and inexpensive mounting which will overcome the foregoing difficulties.

The invention is illustrated in the accompanying drawings, in which—

Fig. 1 is a front elevational view of a transformer container of the bell ringing type, showing a mounting embodying my invention in connection therewith,

Fig. 2 is a rear elevational view of the same, and

Fig. 3 is a side elevational view with the container partially broken away and the mounting back in vertically section.

The container 5 is shown as having generally parallel side walls 6, 6 and generally parallel top and bottom walls 7 and 8 closed at the front by a front wall 9 and open at the back at 10. It is preferably

made of porcelain or other suitable insulating material. The transformer coils (not shown) are usually sealed in the case or container 5 by means of a suitable sealing substance 12. The primary leads or conductors which lead in to the primary coil are indicated at 14 and they extend in through suitable openings 15 in the bottom wall 8. The secondary terminals are indicated at 16 and they lead out through openings 17 in the top wall 7.

The mounting of the container 5 comprises a relatively thin back 20 conveniently of pressed sheet metal. The width of the back 20 is substantially equal to the width of the open back 10 of the container 5 and at the top and bottom of the container the ends of the back 20 are offset at 21 to form mounting flanges or margins 22 substantially parallel to the back of the container and projecting upwardly and downwardly from the top and bottom thereof. These parallel flanges or margins 22 are adapted when attached to the support 23 to support the container 5 in spaced relation thereto. For attaching the back to the support, the flanges or margins 22 may have apertures 24 through which suitable screws 25, for example, may be inserted.

Along the opposite vertical edges of the intermediate portion of the back 20 integral flanges 26 are turned out at substantially right angles to the back and these project into the container 5 when the back is mounted thereon and just fit between the sides 6, 6 to properly position the back transversely upon the container. The container 5 is confined vertically between a pair of integral ears 28 and 30 stuck out from the back at the top and bottom of the container and projecting out at substantially right angles to receive the container between them. These ears 28 and 30 properly position the back and container vertically relative each other and it is through them that the back is secured to the container. The inner surfaces of the upper and lower container walls 7 and 8 have central grooves 32 extending from front to back and screws 34 having heads engaging in and held against turning by the sides of these grooves extend out through the top and bottom walls 7 and 8. These screws 34 are held axially in place by the sealing compound or substance 12. One of the ears 28, 30 is apertured at

35 and the other is slotted at 36 and the screws 34 extend through the aperture and slot in these ears and engage in nuts 38 which bind the mounting back firmly in place. By aperturing one ear and slotting the other, the apertured ear may be inserted over its fastening screw and the other ear may be sprung over the opposite wall of the container and into place over its fastening screw.

The mounting which I have provided is simple and inexpensive and it permits of the employment of a porcelain or other frangible container with its advantages, 15 without the problem of fracturing or breaking off the mounting lugs, in transportation, handling or mounting of the device. Furthermore, the base members or backs may be packed and shipped or transported separately from the containers, making for greater compactness and eliminating that precaution that has heretofore been necessary in packing integrally lugged containers.

25 I claim:

1. A sheet metal back for containers of the class described provided with lateral flanges for engaging internally within the container and between opposite sides thereof, lateral portions for receiving the container between them and for externally engaging opposite sides of the container, means for securing the container to said back and means on said back for attaching 35 the container to a support.

2. In combination, a frangible container having threaded studs held against turning and projecting from opposite walls thereof, a back having lugs for receiving 40 the container between them and for attach-

ment over said threaded studs, said back having offset ends for attachment to a support, and marginal flanges entering the container and positioning the back thereon.

3. In combination, a frangible container 45 having threaded studs held against turning and projecting from opposite walls thereof, a sheet metal back having offset ends for attachment to a support, said back having out-turned marginal flanges at its opposite side adapted to enter the container and to fit between the opposite side walls thereof, out-turned lugs adjacent the offsetting of the opposite ends of the back and fastening means projecting from opposite walls 55 of the container and through said lugs.

4. In combination, a frangible container open at its rear, a sheet metal back of substantially the width of the rear opening of the container and having marginal flanges 60 entering the container and projecting lugs for receiving the container between them, said back having offset projecting flanges for attachment to a support and means for securing the container between said lugs.

5. A sheet metal back for containers of the class described provided with two pairs of integral flanges, one pair turned laterally for internally engaging opposite sides of the container and the other pair turned in 70 a direction opposite said first flanges and adapted for attachment to a support, and lugs turned laterally from the metal of said last flanges in the direction of said first flanges and adapted for receiving the 75 container between them and for externally engaging opposite sides thereof.

In witness whereof I hereunto subscribe my name this 15th day of November, 1924.

JAMES C. DALEY.
